Royal W. France ATTORNEY

UNITED STATES PATENT OFFICE.

DANIEL E. ERICKSON, OF MAMARONECK, NEW YORK, ASSIGNOR TO TODD SHIPYARDS CORPORATION, OF NEW YORK, N. Y., A CORPORATION OF NEW YORK.

LIQUID-FUEL BURNER.

1,381,459.

Specification of Letters Patent. Patented June 14, 1921.

Application filed April 9, 1920. Serial No. 372,505.

To all whom it may concern:

Be it known that I, DANIEL E. ERICKSON, residing in Mamaroneck, in the county of Westchester and State of New York, have 5 invented certain new and useful Improvements in Liquid-Fuel Burners, of which the following is a full, clear, and exact description, such as will enable others skilled in the art to which it appertains to make and use 10 the same.

This invention relates to liquid fuel burners, and more particularly to improved spray nozzles of such devices.

It is an object of the invention to provide 15 a simple and efficient nozzle of the character mentioned, which is reliable and economical in use and which is of few parts not likely to get out of order.

A further object is to provide an improved 20 atomizing device for liquids which possesses features of structural superiority and functional advantages.

A further object is to combine an efficient 25 burner, strainer and atomizer in one device.

Other objects and advantages will be in 30 part noted hereinafter in connection with the following description of the accompanying drawings, which illustrate a preferred embodiment of the invention and wherein,

Figure 1 is a central longitudinal section, and

Fig. 2 is a top view with the retaining cap and diaphragm removed.

Referring more particularly to the drawings, there is shown a pipe or liquid conduit 1 having a threaded connection at its end with a nozzle tube 2. This nozzle tube is provided with a central bore 3 which is enlarged toward the outer end to constitute a chamber 4, and a recess 5 separated by a circular ledge or shoulder 6. An atomizing and straining cylinder 7, which may be of brass or other suitable metal, is provided to fit within the chamber 4, and seat at its inner 45 end against the shoulder dividing said chamber and the bore 3. The walls of cylinder 7 are foraminous, having a number of small apertures 8 therethrough, and the outer end of the cylinder is closed by an integral cap 50 having an overhanging flange 9 with opposite straight sides 10 and intermediate curved sides 11. The dimension of flange 9 is such as to fit the tube recess 5 and support the cylinder on shoulder 6 with the aper- 55 tured walls of the cylinder spaced, as shown,

from the walls of chamber 4 so that the liquid may pass therebetween. The outer surface of the cap flange 9 has a central small and circular recess 12 communicating with the straight sides 10 by tangential 60 channels or grooves 13. In the embodiment of my invention shown in the drawing two of these grooves, opposite one another are shown, but in some circumstances a larger number of grooves may be employed. 65

A flat disk 14, comprising a diaphragm, has a central discharge orifice 15 and is positioned over the outer end of the nozzle tip and is retained by a threaded cap 16 which screws on the outer end of the nozzle. 70 The dimension of the parts described is such that the cylinder 7 is free to rotate, while the nozzle tube, the disk 14 and cap 16 are relatively rigid and fast together.

In operation, oil, or suitable liquid, enters 75 the tube bore 3 under pressure, and is forced through cylinder apertures 8, being somewhat broken up and strained thereby and then passes outwardly and enters through channels 13 to recess 12 of the cylinder end. 80 Passage of the liquid through the channels 13, as described, imparts rotation to the liquid whereby the oil is further broken up and atomized prior to its discharge through disk aperture 15 to be ignited. 85

The construction and operation of the burner, as described, tend to prevent any clogging of the liquid therein and also insure a discharged spray of uniform character. It will be understood, of course, that 90 my improved burner may be employed in furnaces and wherever desirable.

Having thus described my invention, what I claim as new, and desire to secure by Letters Patent is:

1. The combination in a liquid fuel atomizer of a nozzle comprising an integral body portion having an end recess and a bore of two, succeeding diametrical dimensions, whereof the forward dimension exceeds the 100 rearward dimension, a perforated cylinder having one open end and a closure plate at its other end, said plate co-acting with the nozzle end to comprise a chamber for the reception of fuel prior to its emission, said 105 plate centeringly engaging in the aforesaid recess, and said cylinder at its open end engaging the rearward or smaller bore-portion of the body portion of the nozzle, whereby an annular chamber for fuel passage is com- 110

prised between the perforated cylinder and larger bore-portion, close to the fuel reception chamber, and means of communication between said annular chamber and fuel reception chamber.

2. An atomizer for liquid fuel comprising a nozzle portion whose axial bore is concentrically enlarged toward its forward end, and whose forward extremity is provided 10 with a still larger concentric recess, a hollow, perforated cylinder, open at one end, fitting in the smaller diametral portion of said nozzle and forming with the larger diametral portion of said nozzle an annular 15 chamber that is in communication with the nozzle interior by way of the perforations through said cylinder, a forward end

closure for said cylinder in form of a plate which fits said concentric recess, said plate having reduced side portions, to provide 20 clearance spaces in said recess, a central, circular chamber in the front face of said plate and tangential slots communicating from said side portions to said chamber for the flow of liquid fuel thereto, and end closure 25 means for said nozzle and plate with an orifice for the efflux of atomized fuel from said central chamber.

In witness whereof, I affix my signature in the presence of two witnesses.

DANIEL E. ERICKSON.
